UNITED STATES PATENT OFFICE.

OTIS A. MYGATT, OF NEW YORK, N. Y.

COMPOSITE ELECTRICAL LAMP AND PRISMATIC-GLASS REFLECTOR.

No. 823,619.

Specification of Letters Patent.

Patented June 19, 1906.

Application filed March 31, 1904. Serial No. 200,981.

To all whom it may concern:

Be it known that I, OTIS A. MYGATT, a citizen of the United States, residing at New York, in the county of New York and State of New York, have invented certain new and useful Improvements in Composite Electrical Lamps and Prismatic-Glass Reflectors, of which the following is a specification.

My present invention relates to electric lamps with prismatic-glass reflectors, and comprises certain improvements the novel features of which are pointed out in the appended claims.

The lamp embodying my invention is represented in the drawings, in which—

Figure 1 is a side view of the lamp complete; and Fig. 2 is a view showing the reflector and support therefor in cross-section, with the bulb in elevation.

My invention relates to that type of lamp in which the light distribution is such as to give a uniform illumination over a circular area the diameter of which is substantially equal to the distance of the illuminated plane from the lamp. This result has heretofore been accomplished by means of a reflector-lamp having a spherical bulb, the major portion of the surface of which is frosted and in which the illuminant or filament is generally eccentrically located. The reflector for such lamp is generally of less maximum diameter than the maximum diameter of the bulb and fits closely over the unfrosted or clear portion of the bulb. With this construction an accumulation of heat takes place, so to speak, about the filament. This has a tendency to shorten the life of the lamp and in some instances to cause an electric discharge to take place in the lamp between the leading-in conductors. When such a discharge takes place, the lamp may be destroyed. In order to avoid these troubles, which sometimes appear, and at the same time preserve the light-distributing characteristic of the lamp and enhance its appearance, I have devised the following construction: In place of the closely-fitting metal reflector I provide a prism-glass reflector 1, in which prisms of the double-reflecting type are located on the outer side of the reflector, generally as indicated in

Fig. 1. This reflector has a grooved upper edge 2 and fits within a perforated shell 3, either formed integral with or spun onto the outer shell 4 of the lamp-socket. The shade 5 is held in place by means of inwardly-bent fingers 5, cut from the material of the shell 3.

An incandescent lamp is screwed into the socket, as shown in Fig. 2, and comprises a spherical bulb 6, frosted up to a line 7 above the center, Fig. 1. The filament 8 is generally eccentrically mounted, so as to be cut by the plane separating the frosted and unfrosted portions of the bulb or globe. The parts are so arranged that when the lamp is screwed into place a space 9 separates the lamp from the shade and provides a passage for ventilating and cooling currents of air which find their outlet through the perforations 10 in the shell 3. The shade 1 is shaped so that the parts adjacent to the upper part of the lamp conform in curvature therewith, thus making the space 9 of uniform depth throughout a considerable area. Beyond this the shade flares outwardly, as indicated. The effect of the resultant combination of a shade of the character and configuration shown with a lamp of the type indicated is to produce a light distribution, such as heretofore described, but without involving the troubles heretofore present in the operation of the lamp. As the shade conforms in outline to the outline of the upper part of the lamp, but allows a ventilating-space between the lamp and shade, the reflector will act as efficiently within its capacity as would a silvered or other reflecting surface directly on the bulb, while the accumulation of heat will be avoided. The outer rim 11 of the reflector projecting beyond the exterior of the bulb tends to reflect rays which might otherwise pass obliquely upward and also presents an ornamental and illuminating surface in downward direction when the lamp is suspended.

What I claim herein as new, and desire to secure by Letters Patent of the United States, is—

1. The combination of a socket, an incandescent lamp therefor having a spherical bulb a portion of the surface of which is of clear glass and the major portion frosted, a filament located eccentrically in the bulb of said lamp, a reflector-holder formed as a permanent part of the socket, and a prism-glass reflector carried thereby in proximity to the bulb of said lamp but out of contact therewith.

2. The combination of a socket, an incandescent lamp having a spherical bulb the surface of which is frosted except over a zone the maximum diameter of which is less than the maximum diameter of the bulb, a filament in said lamp located in or near the plane

separating the frosted from the unfrosted portions of the bulb, and a prism-glass reflector carried by the socket and shaped so that a portion thereof conforms in curvature with the curvature of the bulb leaving a space between while the outer portion of the reflector is flared out from the bulb.

3. The combination of an incandescent lamp having a spherical bulb frosted except over a zone less in diameter than the maximum diameter of the bulb, a filament in the bulb located so as to be approximately in the plane separating the frosted and unfrosted

portions of the bulb, a prism-glass reflector having an outwardly-flared edge, extending ¹⁵ outwardly beyond the greatest diameter of the bulb, but covering only the upper part of the bulb and leaving a ventilating-space between.

In testimony whereof I affix my signature ²⁰ in presence of two witnesses.

OTIS A. MYGATT.
